S. ADAMS.
MACHINE FOR MAKING WIRE SCREENS, &c.

No. 79,176.

Patented June 23, 1868.

Inventor:
Sanford Adams.

United States Patent Office.

SANFORD ADAMS, OF BOSTON, MASSACHUSETTS.

Letters Patent No. 79,176, dated June 23, 1868.

IMPROVED MACHINE FOR MAKING WIRE SCREENS, &c.

The Schedule referred to in these Letters Patent and making part of the same.

TO ALL WHOM IT MAY CONCERN:

Be it known that I, SANFORD ADAMS, of Boston, in the county of Suffolk, in the State of Massachusetts, have invented new and improved Tools for the Purpose of Making Wire Riddles and Screens; and I do hereby declare that the following is a full and exact description thereof, reference being had to the accompanying drawings, and to the letters of reference marked thereon, in which—

Figure 1 is a plan of a riddle or screen held in the jaws B C.

Figure 2, a section upon the line L L of fig. 1, showing the manner in which the screen is held in the jaws or vise while the wire α is being bent into its proper position.

Figure 3 shows the tool used for rolling the wire lacing α down between the parallel wires of the screen, and also the position and shape of the lacing-wire α before and after the tool G has been rolled over it.

Like letters represent like parts in all the figures.

The nature of my invention consists in constructing a tool in such a manner that by it the lacing-wire in screens or riddles may easily, rapidly, and effectually be bent down between the parallel wires to keep them in position; also in constructing jaws and guides in such a manner that the screens are held firmly in position while being laced and fastened.

To enable others skilled in the art to make and use my invention, I will proceed to describe its construction and operation.

In the said drawings, A A is the frame of the screen. $b b$ are the parallel wires. $c c$ are the cross-wires, to which the parallel wires are fastened. $\alpha \alpha$ are the lacing-wires. B and C are jaws, which hold the screen while being laced. F F' are guides, which hold the parallel wires at equal distances apart, (while being laced,) by means of recesses, either square or V-shaped, cut into the upper edge of the guides, as shown in fig. 2.

I I are connections, which hold the guides F F' together and keep them in an upright position.

E E are bolts, by which the jaws B and C are drawn together. D D are nuts, by which the jaws are tightened upon the screen.

G is the revolving crimpler, with teeth $n n$ and spurs $x x$.

The crimpler G is held in the handle H, and turns on the pin J.

Operation.

The jaws B and C, when brought together, force the parallel wires $b b$ into the notches in the guides F F', as shown in fig. 2, and the parallel wires are held firmly in their places, while being laced and rolled, by the crimpler G.

The guides being fastened together by the connections I I, are always held in an upright position between the jaws B and C, ready to receive the parallel wires whenever they are placed on them.

The lacing-wire α , when first put on, takes the shape as shown on the left of fig. 3, but by rolling and pressing the revolving crimpler G along the lacing-wire α , the teeth $n n n$ on the crimpler force the lacing-wire down between the parallel wires $b b$, and hold them firmly in position, as shown on the right-hand part of fig. 3.

The crimpler G is provided (in addition to the teeth $n n$) with long spurs, $x x x$, which reach down between the parallel wires $b b$, and guide the crimpler G along on the lacing-wire α , bringing the teeth $n n n$ on to the lacing-wire α between the parallel wires. Thus the lacing-wire is effectually crimped upon the parallel wires, and holds all the wires of the screen firmly in position.

What I claim as my invention, and desire to secure by Letters Patent, is—

1. The revolving crimpler G, provided with teeth $n n n$, either with or without spurs $x x$, when arranged and operated substantially as described, and for the purpose set forth.
2. The jaws B and C, when arranged to hold the parallel wires into the guides F F', substantially as described and set forth.
3. Connecting the guides F F' together by the connecting-pieces I I, to keep them in position, substantially as and for the purpose set forth.

SANFORD ADAMS.

Witnesses.

A. G. H. WOOD,

M. MORAH, Jr.
